UNITED STATES PATENT OFFICE.

EDWARD CIECHOMSKI, OF PHILADELPHIA, PENNSYLVANIA.

SHAVING MUG.

Application filed December 16, 1922. Serial No. 607,277.

To all whom it may concern:

Be it known that I, EDWARD CIECHOMSKI, a citizen of Poland, residing at Philadelphia, in the county of Philadelphia and 5 State of Pennsylvania, have invented certain new and useful Improvements in Shaving Mugs, of which the following is a specification.

My invention relates to shaving mugs, 10 more particularly of a type having soap feeding means in the handle and has for its object to provide a mug of a simple and compact construction having shaving soap feeding means and still retaining the neat 15 appearance of a mug.

These objects, and other advantageous ends which will be described hereinafter, I attain in the following manner, reference being had to the accompanying drawings in 20 which—

Figure 1 is a side elevation of a mug constructed in accordance with my invention,

Figure 2 a top plan view of Figure 1,

Figure 3 a section on line 3—3 of Figure 2,

25 Figure 4 a section on line 4—4 of Figure 3, and

Figure 5 a view similar to Figure 4 showing the cross section of another form of handle.

30 Referring to the drawings, the mug comprises a cup 6 having secured thereto in spaced relation a hollow handle 7 by means of a tube 8 communicating with the interior of the cup and handle, and a band 9. A 35 piston 10 slides within the handle and has a threaded rod 11 passing therethrough to which is secured a turning knob 12 having an annular groove 13. A cap 14 is mounted in groove 13, to permit rotation of knob 12, 40 and is detachably secured to the handle by any suitable means, preferably a threaded connection, and thus holds the rod against endwise movement. A spine 15 prevents rotation of the piston by reason of the notch 45 16 sliding over it.

Referring to Figure 5, the handle 7^a is 50 elliptical in cross section and has a piston 10^a conforming to the shape of the interior thereof. In this form no spline is necessary for preventing rotation of the piston. In all other respects the handle is similar to that shown in Figure 4 and similar parts are given corresponding reference characters.

55 To fill the mug, cap 13 is removed, the

piston slid out of the cylinder, and the handle filled with paste soap. The piston is positioned on the threaded rod adjacent the cap and then placed in the handle, the cap secured and the mug is ready for use. In 60 use, when it is desired to feed soap it is merely necessary to turn knob 12 which will cause the piston to force the soap through tube 8 into the cup. Thus through a simple manipulation of the turning knob any 65 desired quantity of soap may be fed.

While I have described my invention as taking a particular form, it will be understood that the various parts of my invention may be changed without departing from the 70 spirit thereof and hence I do not limit myself to the precise construction set forth, but consider that I am at liberty to make such changes and alterations as fairly come within the scope of the appended claims. 75

Having thus described my invention, what I claim as new and desire to secure by Letters Patent is:—

1. A shaving mug including a cup, a hollow handle at the side of the cup in spaced relation with respect thereto for the reception of shaving material, a conduit opening communication between the cup and handle, and a member movable within the handle adapted to force the shaving material into 80 the cup.

2. A shaving mug including a cup, a hollow handle at the side of the cup in spaced relation with respect thereto for the reception of shaving material, a conduit opening communication between the cup and handle and serving as the handle attaching means, and a member movable within the handle adapted to force the shaving material into 90 the cup.

3. A shaving mug including a cup, a hollow handle for the reception of shaving material, means connecting the handle to the cup and opening communication between the handle and the cup, and a movable member within the handle adapted to force the shaving material into 95 the cup.

4. A shaving mug including a cup, a hollow handle for the reception of shaving material in communication with the cup and provided with a longitudinally extending member interior thereof, a rotatable threaded member extending into the handle and provided with operating means, and a member within the handle and movable by the 105 110

threaded member and having a notched portion receiving the longitudinally extending member.

5. A shaving mug including a cup, a hollow handle in communication with the cup for the reception of shaving material, a rotatable threaded member within the handle and provided with an operating knob having an annular groove formed therein, a cap for the handle and engaging the groove, and a member movable within the handle

and movable upon rotation of the threaded member adapted to force the shaving material into the cup.

In testimony whereof I have signed my name to this specification in the presence of two subscribing witnesses.

EDWARD CIECHOMSKI.
